UNITED STATES PATENT OFFICE.

AMOS H. SMITH, OF NEW YORK, N. Y., ASSIGNOR TO AMERICAN BANK NOTE COMPANY,
A CORPORATION OF NEW YORK.

METHOD OF MAKING MULTICOLOR PRINTS.

1,294,719.

Specification of Letters Patent. Patented Feb. 18, 1919.

Application filed May 13, 1915. Serial No. 27,774.

To all whom it may concern:

Be it known that I, AMOS H. SMITH, a citizen of the United States, residing at the borough of Bronx, city of New York, county 5 of Bronx, and State of New York, have invented certain new and useful Improvements in Methods of Making Multicolor Prints, of which the following is a specification, reference being had therein to the 10 accompanying drawings, which form a part thereof.

My invention relates to a method of making multi-color prints and more particularly to a method by which certain effects secured 15 by different printing methods may be secured during a single run of the sheet to be printed.

My invention is particularly adapted for producing work having a background tint 20 and matter superimposed thereon in a contrasting tone or color. Heretofore the commercial practice in producing work of this character has been to first make an impression upon the paper from a planographic 25 or cameo printing surface, bearing thereon a design having a tint effect, or from a transfer surface upon which the design of such tinted plate has been offset. Where the printing has been directly from the tinted 30 planographic surface, dampened sheets of paper have been used but when printing from an offset surface or from a cameo printing surface, dry paper has been used. After this impression of the tint has been made 35 upon the paper, the paper is allowed to stand until the ink is dry and subsequently it was run through a second press having a printing surface consisting of an engraved, intaglio or undersurface printing plate. 40 This class of work is usually employed in the production of "safety" papers, such as bank-notes, checks, bonds, stock certificates, drafts, coupons and other negotiable instruments.

When the tint effect is printed upon dry paper, it has been necessary to dampen this paper before making the impression thereon from the engraved, intaglio or undersurface printing plate; and when the tint 55 effect is impressed upon the paper by a planographic surface, it has been necessary to re-dampen the paper before making an impression thereon by means of the engraved, intaglio or undersurface plate. Hence, by the old method, each impression

upon the paper was made under different conditions and in making the impression from the engraved, intaglio or undersurface plate great care was necessary to secure accurate register, and uniformity, in the 60 product.

To obviate the difficulties of the existing practices, it has been suggested that paper of this character be printed at a single impression, this proposed method or art involving the offsetting of the tinted design upon the non-printing surface of the engraved, intaglio or undersurface plate and the making of a single multi-color impression from this plate upon the paper. While this 70 method has its advantages as compared with the methods usually practised, it is subject to the criticism that it entails the practice of different printing methods under those conditions particularly adapted to but one of 75 these methods. The conditions surrounding the printing from an engraved, intaglio or undersurface plate differ radically and fundamentally from the conditions present in printing from an ordinary cameo printing 80 surface or from a planographic surface, not only as to pressures and speeds but as to the nature of the ink employed. Hence, the best results cannot be secured by means of this proposed method.

By extensive experiments, I have determined that it is not essential in producing the so-called "safety" papers to allow the tint impression to dry before making the superimposed impression thereon from the 90 engraved, intaglio or undersurface plate, nor to make these impressions simultaneously; but that paper of this character can be successfully produced by a continuous method wherein the tinted background is 95 impressed upon dampened paper conditioned for use in connection with an engraved, intaglio or undersurface plate and the impression from an engraved, intaglio or undersurface plate is superimposed thereon immediately thereafter. By this method the background may be printed under those conditions particularly adapted to the printing method employed in making the background impression, and the impression from 100 the engraved, intaglio or undersurface plate may be made under those conditions particularly adapted for this method of printing. At the same time, although, impressions under the two methods are made suc- 110

cessively, the time element is identical with that of the single impression method, and has the same advantages over the methods now practised, as a single impression method would.

By my present invention I am enabled to limit the quantity of ink upon the tinted impression, to maintain uniformity in succeeding impressions and to prepare the surface 10 of the paper for the final impression from the engraved, intaglio or undersurface plate by making it perfectly smooth.

The invention consists primarily in the method or art of making multi-color prints 15 consisting in inking a printing surface having a tint design thereon, offsetting said design upon an elastic surface, transferring the design from said elastic surface to a surface having a smooth, polished, non-elastic, metallic surface, preparing a printing surface having a design thereon to be superimposed upon said tint design and making an impression upon the paper first from said hard polished, non-elastic, metallic surface 20 and immediately thereafter from said other printing surface as are hereinafter set forth and described and more particularly pointed out in the claims hereto appended.

In the accompanying drawings, I have 30 shown diagrammatically two forms of apparatus which may be used in the practice of my method or art.

Referring to the drawings:—

Figure 1 is illustrative of one form of apparatus capable of use in the practice of my method or art wherein two impression cylinders, or D-rolls, are employed, one in relation to the smooth, polished, non-elastic, metallic surface and the other in relation to 40 the other surface, a transfer cylinder co-operating with each of said impression cylinders or D-rolls being employed in reversing the sheet in feeding it from one of said impression cylinders or D-rolls to the other.

Fig. 2 is a modification thereof wherein two impression cylinders, or D-rolls, are employed, one in relation to said smooth, polished, non-elastic, metallic surface and the other in relation to the other surface, the last named impression cylinder, or D-roll, removing the paper from said first named printing surface; and

Fig. 3 is a further modification thereof illustrative of a form of apparatus for carrying out the invention employing a single impression cylinder, or D-roll with both said smooth, polished, non-elastic, metallic surface and said other printing surface.

Like letters refer to like parts throughout the several views.

In the form of the invention illustrated, I have shown the engraved, intaglio or undersurface printing surface as being a flat plate, although a curved plate upon a form

cylinder may be used instead of this flat plate, and its horizontally movable bed.

In the practice of my improved method or art, I prepare a printing surface consisting of a smooth, polished, non-elastic, metallic surface by inking a surface having thereon a design having a tint effect, from which surface, I offset the tinted design upon an elastic surface and transfer the design from this elastic surface to said smooth, polished, non-elastic metallic surface. After each impression I subject this smooth, polished, non-elastic metallic surface to the action of a wiper to thoroughly cleanse it and remove all parts remaining after making the impression therefrom.

I also prepare a steel engraved, intaglio or undersurface printing plate by inking, wiping and polishing in the usual manner and thereafter making impressions upon a sheet of paper first from said smooth, polished, non-elastic, metallic printing surface bearing the tinted design upon the surface thereof and immediately thereafter from said steel engraved, intaglio or undersurface plate. Inasmuch as the tint impression is made from a perfectly smooth, polished plate very light pressure upon the paper is required to make the desired impression but when making the impression from engraved, intaglio or undersurface plates relatively greater pressure is required to force the paper within the lines of the plate in a manner to secure the desired sharp, clear-cut impression.

The paper before receiving the impression from the smooth, polished plate is dampened and as the impression is being made from said smooth, polished surface the continuity of this surface will have the effect of pressing the paper in a manner to cause it to present a perfectly smooth surface to the engraved, intaglio or undersurface plate.

The two impressions being made one immediately after the other does not allow sufficient time for the paper to dry sufficiently to allow such shrinkage as to necessitate its being re-dampened before the second impression is made and the manner of making the tinted impression is such as to avoid the necessity for the drying of the ink for this impression prior to the making of the second impression. The manner of making the imprints is such as to insure accuracy in the register of the two impressions which accuracy results from the make-ready of the machine and is not dependent in any way upon the condition of the paper.

I have found that by making the tinted impression first, the desired delicate background may be secured and the subsequent impression from the undersurface printing plate does not in any way interfere with the tinted impression. If desired, the design upon the tinted printing surface may be

such as to leave blank spaces for the matter to be superimposed thereon.

These conditions result from the well-known fact that in making a tinted impression, the surface of the paper remains perfectly smooth which is not the case when printing from an undersurface plate.

- By making consecutive impressions, the tinted impression may be made with comparatively light pressure while the impression from the undersurface printing plate, may be made with a relatively greater pressure such as is required in this method of printing.
- 15 The ink used in preparing the printing surface bearing the tint design is that ordinarily employed in planographic work and with offset presses; and that used upon the engraved, intaglio or undersurface plate is that ordinarily used in undersurface printing.

Referring to Fig. 1 of the accompanying drawings, *a* represents a cylinder adapted to receive a plate *b* bearing thereon a design 25 having a tint effect which may be made by means of a pantograph, photo-engraving or any other desired or well-known method.

Coöperating with said cylinder *a* is an inking mechanism comprising an ink fountain *c*, distributing rollers *d* and inking rollers *e*.

Associated with the cylinder *a* is a second cylinder *f* having thereon an elastic surface *g* upon which the design upon the plate 35 *b* is adapted to be offset.

At *h* is a cylinder carrying a printing surface *i* consisting of a non-elastic, metallic plate having a continuous smooth, polished surface. The relation of the cylinders *h* to 40 the cylinder *f* is such as to cause the design upon the elastic surface *g* to be transferred upon the metallic surface *i* which serves as a printing surface from which the tinted impression upon the paper is made. Associated with the cylinder *h* is a wiping mechanism *j*, the function of which is to remove the residue of ink upon the plate *i* after the making of each impression, in a manner to prevent such changes in the condition of this 45 surface *i* as would, after a prolonged run, result in a strengthening of the impression made therefrom.

Adjacent the cylinder *h* is a movable support *k* adapted to carry an engraved, intaglio or undersurface printing plate *l* and associated with said support are an inking mechanism *m*, a wiping mechanism *n* and a polishing mechanism *o*.

Coöperating with the cylinder *h* is an impression cylinder, or D-roll, *p* and coöperating with the support *k* is a second impression cylinder or D-roll *q*. Coöperating with each of the impression cylinders *p*—*q* is a transfer cylinder *r* adapted to receive 55 printed sheets from the cylinder *p* reverse

them and deliver them to the impression cylinder, or D-roll *q*, in a manner to cause the impression from the surface *i* and from the plate *l* to be superimposed one on the other.

70 A feed shelf *s* is positioned adjacent the impression cylinder or D-roll *p*.

In Figs. 2 and 3 I have shown two forms of apparatus for use in the practice of my method or art wherein the arrangement of the printing surface and the mechanisms for preparing the same are like those shown in connection with the apparatus illustrated in Fig. 1 and above described. The apparatus shown in Figs. 2 and 3 differ from 80 the apparatus shown in Fig. 1 merely as to the arrangement and relation of the impression cylinder or cylinders in relation to said printing surface.

In Fig. 2 of the drawings, I employ two 85 impression cylinders *t*—*u* one associated with the cylinder *h*, and the other with the support *k*. The paper is fed from the feed shelf *s* to the impression cylinder, or D-roll, *t*, and the impression cylinder or D-roll *u* receives the sheet of paper from the cylinder *h* after the impression has been made thereon and brings it into engagement with the plate *l*.

In the apparatus shown in Fig. 3, I employ a single impression cylinder or D-roll *v* common to and adapted to coöperate with, both the cylinder *h* and the support *k* so as to receive the paper sheet from the feed shelf *s* and bring it into engagement with the 100 printing surface *i* and the printing plate *l* successively, while it is still on this cylinder *v*.

In the different types of apparatus shown it will be observed that the paper is printed by a continuous method and that multi-color prints are secured by a single run of the paper through the machine, and that each impression will be made under exactly the same conditions as to the paper.

I am aware that in some three-color methods, successive impressions have been made from a plurality of photo-engraved plates upon succeeding cylinders, but in this type of work but one printing method is employed and the conditions are not such as are found in high class commercial printing.

110 My invention is distinguished from the ordinary three-color printing method, in that I am enabled to secure multi-color work by means of radically and fundamentally different printing methods and under conditions which are not found in the ordinary three-color methods such as differences in the character of the ink, in the character of the 115 printing surface and in the pressures to which the paper must be subjected to secure the desired character of impression.

120 By my invention, I am enabled to produce, by a continuous method, a completed print 125

having a tinted background, the qualities of which will equal that produced by the methods now being used and which have been referred to above. By this method I avoid 5 all likelihood of a loss of register and am enabled to produce completed work in much less time than that required by the methods at present practised.

Having described the invention, what I 10 claim as new and desire to have protected by Letters Patent is:—

1. The method or art of making multi-color prints consisting in inking a printing surface having a tint design thereon, off-15 setting said design upon an elastic surface, transferring the design from said elastic surface to a surface having a smooth, polished, non-elastic, metallic surface, preparing an engraved, intaglio, or under-surface print-20 ing plate having a design thereon to be superimposed upon said tint design, and making an impression upon the paper, first under light pressure from said smooth, polished, non-elastic, metallic surface, and im-25 mediately thereafter under relatively greater pressure from said other printing plate.

2. The method or art of making multi-color prints consisting in inking a printing surface having a tint design thereon, off-30 setting said design upon an elastic surface, transferring the design from said elastic surface to a surface having a smooth, polished, non-elastic, metallic surface, inking, wiping and polishing an engraved, intaglio or un-35 dersurface plate having a design thereon to be superimposed upon said tint design and making an impression upon the paper, first under light pressure from said smooth, polished, non-elastic, metallic surface and im-40 mediately thereafter under relatively greater pressure from said engraved intaglio or un-undersurface printing plate.

3. The method or art of making multi-color prints consisting in inking a printing 45 surface having a tint design thereon, off- setting said design upon an elastic surface, transferring the design from said elastic surface to a surface having a smooth, polished, non-elastic, metallic surface, inking, 50 wiping and polishing an engraved, intaglio or undersurface plate having a design thereon to be superimposed upon said tint design and making an impression upon dampened paper, first from said smooth, polished, 55 non-elastic, metallic surface and im- mediately thereafter from said engraved intaglio or undersurface printing plate, the

said paper being subjected to different pressures when making said impressions respectively, the pressure upon the last named 60 impression being relatively greater than upon the first impression.

4. The method or art of making multi-color prints consisting in superimposing a plurality of impressions upon a sheet of 65 paper, one immediately after the other, the first impression being made from an ink design upon a smooth, polished, non-elastic, metallic surface and the second impression being made from an inked, polished and 70 wiped engraved, intaglio or undersurface printing plate.

5. The method or art of making multi-color prints consisting in superimposing a plurality of impressions upon a sheet of 75 paper, one immediately after the other, the first impression being made from an ink design upon a smooth, polished, non-elastic, metallic surface and the second impression being made from an inked, polished and 80 wiped engraved, intaglio or undersurface printing plate and under relatively greater pressure than upon the preceding impression.

6. The method or art of making multi-color prints consisting in superimposing a plurality of impressions upon a dampened sheet of paper, one immediately after the other, the first impression being made from an ink design upon a smooth, polished, 85 non-elastic, metallic surface and the second impression being made from an inked, polished and wiped engraved, intaglio or un-undersurface printing plate.

7. The method or art of making multi-color prints consisting in superimposing a plurality of impressions upon a dampened sheet of paper, one immediately after the other, the first impression being made from an ink design upon a smooth, polished, non-elastic, metallic surface and the second impression being made from an inked, wiped and polished engraved, intaglio or under-surface printing plate and under relatively greater pressure than upon the preceding 100 105 impression.

In witness whereof, I have hereunto affixed my signature in the presence of two subscribing witnesses, this 23rd day of April, 1915.

AMOS H. SMITH.
